UNITED STATES PATENT OFFICE.

ALFRED J. DIEBOLD, OF PITTSBURGH, PENNSYLVANIA.

TELEPHONE-RECEIVER HOLDER.

1,345,839.

Specification of Letters Patent.

Patented July 6, 1920.

Application filed April 2, 1919. Serial No. 286,924.

To all whom it may concern:

Be it known that I, ALFRED J. DIEBOLD, a resident of Pittsburgh, in the county of Allegheny and State of Pennsylvania, have 5 invented a new and useful Improvement in Telephone-Receiver Holders, of which the following is a specification.

The invention relates to an attachment for standard telephone receivers arranged 10 to support the telephone receiver from the user's shoulder with the receiver in contact with the ear, whereby the user is enabled to listen in and still have both hands free, and which support does not interfere with the 15 suspension of the telephone receiver from the telephone hook in the usual way.

In the accompanying drawing Figure 1 is an elevation showing a standard desk set with one form of the attachment connected to the receiver, and Fig. 2 is a view of the attachment looking in a direction at right angles to the view of Fig. 1.

In the drawing 1 represents the usual desk telephone stand carrying on its upper 25 end the transmitter 2, and provided with the usual pivoted hook 3 for suspending the receiver 4. The receiver illustrated is a standard form in wide use, and is of a nature that it must be held with one hand 30 while carrying on a telephone conversation. It frequently happens that the party using the telephone must refer to documents and other matters during the conversation, and with one hand occupied in holding the receiver this frequently becomes difficult. In 35 fact it frequently becomes necessary to lay down the receiver and thus interrupt the conversation while hunting for documents or making memoranda, or the like. The 40 purpose of my invention is to provide such standard telephone receivers with means whereby it can be supported from the shoulder of the user and leave both hands free.

The support is arranged to project beyond 45 the outer end of the telephone receiver and slightly to one side, so that when its outer end rests upon the user's shoulder the inner end of the telephone receiver is held in contact with the ear. This support may be 50 variously formed and secured to the telephone receiver in various ways. As shown the support 5 is provided with a widened outer end portion 6 which is curved so as to fit on the shoulder, and has a shank portion 55 7 provided with a clamp 8 arranged to encircle the telephone receiver and be clamped thereto, such as by means of a clamping

screw 9 connecting perforated ears 10 on the clamp. Many other means for securing the supporting member of the telephone receiver can obviously be used. The clamp connection shown permits the support to be adjusted longitudinally on the telephone receiver so that it can be made convenient for various persons. The support projects 60 considerably beyond the outer end of the receiver and to one side thereof, thereby providing an extension of sufficient length and so offset as to firmly hold the telephone receiver against the ear from the shoulder of 65 the user. In order that this support does not interfere with hanging the receiver on the hook 3 in the usual way the shank 5 preferably is offset as at 11, in order to clear the hook 3.

In the use of the telephone with this attachment the receiver will be placed against the ear in the usual way with the supporting member on the lower side thereof, which will bring the end 6 of the support in position so that it will rest upon the shoulder, and by a slight lifting of the shoulder the receiver can be held firmly against the ear, thus leaving both hands 75 free.

The attachment can obviously be made of various forms and of any suitable material and secured to the telephone receiver in various ways. If desired the portion resting on the user's shoulder can be roughened or covered with felt or other material to prevent it from slipping.

I claim:

The combination with a standard telephone receiver comprising an elongate body 95 having the receiving diaphragm at one end and conductor terminals at its outer end, of a substantially rigid supporting member attached to said body member and projecting therefrom beyond said outer end of the receiver in the same general line of extent of the receiver but slightly laterally therefrom, the outer end of said member being provided with a shoulder rest whereby the telephone receiver may be held between an ear 100 and shoulder of a user solely by urging said ear and shoulder toward each other against said rest and the diaphragm end of the receiver.

In testimony whereof, I have hereunto 110 set my hand.

ALFRED J. DIEBOLD.

Witness:

ALICE A. TRILL.
